UNITED STATES PATENT OFFICE.

FREDERIC P. JONES, OF SEACOMBE, ENGLAND.

MANUFACTURE OF BRICKS.

Application filed May 9, 1923. Serial No. 637,823.

To all whom it may concern:

Be it known that I, FREDERIC PHELP JONES, a subject of the King of England, and residing at Seacombe, in the county of 5 Chester, England, have invented Improvements in and Relating to the Manufacture of Bricks (for which an application for patent has been filed in Great Britain April 18, 1922, No. 195,280), of which the following

10 is a specification.

This invention has reference to the manufacture of bricks or blocks, having an artificially roughened surface or finish; and it has primarily for its object and effect to 15 produce a brick having a surface or face of an antique character or appearance, such as many bricks possessed in the sixteenth and seventeenth and eighteenth centuries; and in the manufacture of bricks or blocks as 20 hereinafter described the improvements under this invention are comprised.

According to the method of manufacture under this invention a strip or strips is or are removed from the body of clay or like 25 material of which the brick or block is made by suitable separating means; and then the strip or strips is or are subsequently re-united to the body of the material by pressing means, acting on the surface of same.

30 The improved brick or block, therefore, is characterized in that it consists of a body in which an outer surface part or the outer surface parts which has or have been separated and reunited under pressure locally, 35 while the brick and pressing means are moved relatively to each other.

According to a further feature under this invention, to produce what is considered the best quality or character of antique surface 40 required, the pressing means for re-uniting the strip or strips with the body is capable of limited local movement, or has movement imparted to it to a limited degree, but preferably the presser is capable of a limited 45 local movement or play, and is pressed onto the material by an elastic or yielding medium, or through same.

In the case of the clay or other material 50 from which the bricks or blocks are to be made and which is extruded in and by a machine through a die, it is cut in the longitudinal direction on both sides and the edges, or some of them, by transverse blades, wires, or the like, and near the surface, which extend through the die; and subsequently the 55 strip or strips of clay thus separated from

the body, is or are pressed upon, and it or they is or are re-united with the clay bar or body, which becomes one again. The result of this is that the surface effect or finish desired is accomplished; namely, the surface appearance of or resemblance to antique bricks, such for instance as bricks commonly made in the 16th and 17th and 18th 60 centuries.

When under this invention, therefore, the bricks of the kind referred to are produced by extruding a stream or bar of clay or other material from a machine, a strip or strips of the body of the material of which 65 the bricks are made, is or are separated from the body by blades or wires in the die, and then it or they is or are pressed and joined together or re-united while moving, by pressers or presser bars or plates held in 70 sockets or holders which act on the separated outer laminæ or strips of clay or the like, and press same onto the issuing bar within it; they being normally pressed onto the outer strip or strips by means of springs 75 or elastic medium or weights; through which also as stated the cutter blades, wires or the like extend. Thus the temporary separation or severance of the outer laminae or some of them, and the issuing clay bar, and 80 the reunion of same is effected within the die itself, and near its point of issuance.

The thickness of the separated or severed strips varies in accordance with the desired character of surface finish, say from $1\frac{1}{2}$ " to 90 $2\frac{1}{2}$ " thick, or other dimensions.

In the case of machine moulded bricks, the orifice or duct leading the material into or out of the mould is provided with means for separating, retarding and reuniting the 95 whole as above mentioned.

The invention will be further described with reference to the accompanying drawings, which show the dies and parts used in connection with same, namely, the arrangement of wires or knives, and other parts by which the effects herein described are accomplished.

Figure 1 is an end elevation; Figure 2 is a side elevation partly in section; Figure 3 105 is a plan; and Figure 4 is a plan in section.

In the drawings, 1 represents the die proper through which the clay or material is extruded, 2 are the vertical and transverse wires or knives, and 3 are the pressers 110 which in the case shown are bars.

The stream or bar of clay or other ma-

terial extruded from the die is marked 4, and is represented by the shaded parts in Figure 1, which show the thin strips 4^x at the top, bottom and sides of the bar which are cut off or separated temporarily from the body.

In the case shown, it may be assumed that the separating means 2 are short thin blades, they being held at the ends by bolts 10 6, one of which is threaded, and has a winged nut 7 screwing onto it, by which the blades or wires are drawn up, and the knife held under the required strain or tension. The carrier bolts 6 are supported in brackets 15 8 on the dies 1.

The presser bars 3 lie in sockets 11, and are pressed inwards on to the extruding bar of clay or material by springs 10, by the screw plugs 12 above the sockets 11, and 20 screwing into the end part of the die. The springs 10 press the bars 3 on to the surfaces of the clay or like bar 4 with the required degree of pressure, which may be varied and adjusted to produce different 25 effects on the clay.

The presser bar sockets 11 are provided on the inside of the die, and give freedom of movement or a certain amount of play to the bars, as seen by the drawing; and different 30 adjustments and tensions of the springs produce different surface effects on the bricks; and differential rate of travel between the outer strips 4^x and the bar body 4, which affects the character of the surface 35 produced on the bricks. The bars 3 can thus move in a plane at right angles to the surface of the material or in a parallel direction therewith.

In the case shown in the drawings, the 40 presser bars 3 are placed within the die, but they may if desired be carried and act immediately on its outer edge.

In the case shown the presser bars 3 are immediately in front of the front bar of 45 the separating blades 2.

The die is in two parts, the presser bars being fitted in the front part whilst the separating knives or wires are carried from the back part, on brackets 8 formed thereon; the front portion of the die being carried from the back part by projecting members 50 13, which fit over and lie on the back part, and are bolted thereto.

In the extrusion of the clay, prior to 55 its coming under the operation of the separating knives or wires, the whole bar is being pressed through the die in a stream of the dimensions of the bricks to be made in length or depth, and the stream or bar of 60 clay will be cut into finished bricks transversely. The die at the part where the clay bar is acted upon is of the complete size of bar required, and is acted upon at this part by the knives or wires 2; and where the upper and lower edge surfaces, and the two

end surfaces are to receive the roughened or wrinkled surfaces referred to, there will be four of these separating knives or blades or wires, as in the case illustrated in the drawing.

The separated strips 4^x, which may be about $\frac{1}{4}$ " to $\frac{1}{2}$ " thick, more or less, are separated by the knives or wires 2, and then subsequently they are acted upon by the spring presser bars 3, at a little distance 70 in front of the point where the separation takes place, and preferably near the point of emergence of the clay bar; that is in such a position that they will retard the flow of the separated outer strips. The effect of these spring presser bars, mounted in their sockets so that they can move in them and have play therein as above referred to, is that the surface effect or character specified is produced; the retarding action 75 or effect of the presser bars on the separated strips promoting the production of these effects. That is, a differential rate of movement is produced between the surface of the separated strips, and the remaining portion 80 of the bar of clay or the like, which has or promotes this effect.

In the course of the expression of the bar through the die, and of the expression of the separated portions passed and beyond 95 the presser bars, the whole of the bar becomes reunited into one body, having the roughened or wrinkled or creased surfaces required, the wrinkling or creasing being varied in character somewhat in different 100 parts of the surface, so that the wrinkling is irregularly or differently presented or distributed over the different parts of the surface.

It is to be assumed that the bar of clay is 105 pressed through the die by any known suitable means, and in the case of machine moulded bricks, the machine will be provided with means for separating the strips, and pressing same back on to the body, to 110 reunite the whole and produce the required surface effects at a suitable point.

In some of the attempts to produce the character of surface or face, such as many 115 bricks possessed in the 16th and 17th centuries, the roughened surfaces have been obtained by wires or the like fixed in front of a die or other brick making appliance, by which a portion of the clay bar in the form of strips, was separated, and 120 which was subsequently removed by hand or other means; but the effect and result of this action did not produce the well-known and desired surface character or effect.

In some cases where desired, the parts 125 carrying the separating blades or wires may be adapted to be adjusted on the die so as to act on the bar of clay or the like at different distances from its edge to produce different thickness of separated strips.

By this invention, not only are the surfaces roughened, but as stated they are wrinkled or creased in varying directions all over the surface, which gives the brick 5 the antique appearance or effect required, such as bricks of centuries specified had; and this effect as stated can be varied or modified somewhat by differences of pressure on the presser bars, and differences of 10 amount of freedom or play of same in their sockets, in both directions, in which they are free to vibrate by their action on the clay strips, and their reaction on them; while also the effect will also be varied by 15 the thickness of the separated portions.

What is claimed is:—

1. The manufacture or production of bricks or blocks of the kind referred to, characterized by separating an unbroken 20 slice of the full surface dimensions from the formed body and then reuniting the severed slice to the body by a pressing means capable of simultaneously ornamenting the surface of the slice.
2. A brick or block, means for separating an outer surface part of full surface area and appreciable thickness from such brick, and means for exerting pressure on such separated part to reunite it to the brick.
3. In a machine for making bricks or the like, severing means to cut from the brick body a slice of the full area of the surface and of appreciable thickness, and a presser bar acting on said severed slice 35 to re-unite the same to the body and simultaneously ornament the surface of such slice.
4. In a machine for making bricks or the like, severing means to cut from the brick body a slice of the full area of the surface 40 and of appreciable thickness, and a presser bar acting on said severed slice to reunite the same to the body, said presser bar having a limited free movement in relation to the surface of the slice, whereby to provide 45 a vibratory or variable pressure action.
5. In a machine for making bricks, means

for cutting a plurality of slices from the surfaces of the brick body, and presser bars arranged to unite the severed slices to the body, said bars being adjustable and mounted for limited free movement with relation to the surface of the slice with which they are cooperating. 50

6. In a machine for making bricks, a die member for the formation of the brick outline in two dimensions, means operating in the die for severing surface slices from the formed body, and presser means carried by the die for reuniting the severed slices. 55

7. In a machine for making bricks, a die member for the formation of the brick outline in two dimensions, means operating in the die for severing surface slices from the formed body, and presser means carried by the die for reuniting the severed slices, said 60 presser means having limited free movement to produce an ornamental effect on the surface of the slice with which they are cooperating. 65

8. In a machine for making bricks, a body forming die, material severing means operating within the die, and material pressing means operating within the die, whereby portions of the material are separated from the body and reunited to the same within 75 the die limits.

9. In a machine for making bricks, a body forming die, material severing means operating within the die, and presser bars mounted in the die in advance of the severing means, said presser bars being mounted to permit a limited freedom of movement longitudinally of the die, and means to vary the tension of said presser bars. 80

In testimony whereof I have signed my 85 name to this specification in the presence of two subscribing witnesses.
